United States Patent [19]

Chiang

[11] Patent Number: Des. 299,318

[45] Date of Patent: ** Jan. 10, 1989

[54] ALTERNATING CURRENT SENSING DEVICE

[76] Inventor: John A. Chiang, 113 Belvedere Ct., Walnut Creek, Calif. 94598

[**] Term: 14 Years

[21] Appl. No.: 889,480

[22] Filed: Jul. 25, 1986

[52] U.S. Cl. D10/78; D10/103

[58] Field of Search D10/75, 76, 77, 78, D10/80, 102, 103; 324/117, 127, 156, 149, 158

[57] CLAIM

The ornamental design for an alternating current sensing device, as shown and described.

DESCRIPTION

FIG. 1 is a front and bottom perspective view of an alternating current sensing device showing my new design;

FIG. 2 is a front elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a left side elevational view thereof.

FIG. 1

FIG. 2

FIG. 5

FIG. 3

FIG. 4

FIG. 6

FIG. 7
